US00D759218S

(12) **United States Design Patent**
Young et al.

(10) **Patent No.:** **US D759,218 S**
(45) **Date of Patent:** ** *Jun. 14, 2016

(54) **GASKET HAVING RAISED SEALING SURFACE PATTERN**

(71) Applicant: **Garlock Sealing Technologies, LLC**,
Palmyra, NY (US)

(72) Inventors: **Joseph D. Young**, Palmyra, NY (US);
Stefan Pitolaj, Palmyra, NY (US);
Aydin Aykanat, Palmyra, NY (US);
Earl J. Rogalski, Palmyra, NY (US)

(73) Assignee: **GARLOCK SEALING TECHNOLOGIES, LLC**, Palmyra, NY (US)

(*) Notice: This patent is subject to a terminal disclaimer.

(**) Term: **14 Years**

(21) Appl. No.: **29/520,073**

(22) Filed: **Mar. 11, 2015**

(51) LOC (10) Cl. **23-01**

(57) **CLAIM**

The ornamental design for a gasket having raised sealing surface pattern, as shown and described.

DESCRIPTION

FIG. 1 is a front perspective view of a gasket having raised sealing surface pattern;

FIG. 2 is a top plan view, with the bottom plan view being identical thereto;

FIG. 3 is a front elevation view, with the rear elevation view being identical thereto; and,

FIG. 4 is a right side elevation view, with the left side elevation view being identical thereto.
